UNITED STATES PATENT OFFICE.

JOHN ROGERS FLANNERY AND ETHAN I. DODDS, OF PITTSBURGH, PENNSYLVANIA,
ASSIGNORS TO FLANNERY BOLT COMPANY, OF PITTSBURGH, PENNSYLVANIA.

STAY-BOLT STRUCTURE.

1,293,636.

Specification of Letters Patent.

Patented Feb. 4, 1919.

Application filed May 3, 1918. Serial No. 232,299.

To all whom it may concern:

Be it known that we, JOHN ROGERS FLANNERY and ETHAN I. DODDS, citizens of the United States, and residents of Pittsburgh, 5 in the county of Allegheny and State of Pennsylvania, have invented certain new and useful Improvements in Stay-Bolt Structures; and we do hereby declare the following to be a full, clear, and exact description of the invention, such as will enable others skilled in the art to which it appertains to make and use the same.

This invention relates to improvements in staybolt structures for boilers, and more 15 particularly to the means for closing the outer end of the bearing sleeve,—the object of the invention being to provide simple and efficient means for quickly removing and replacing the closure for the bearing sleeve, 20 to facilitate access to the staybolt for testing purposes.

With this and other objects in view, the invention consists in certain novel features of construction and combinations of parts as 25 hereinafter set forth and pointed out in the claims.

In the accompanying drawings; Figure 1 is a sectional view of a staybolt structure showing an embodiment of our invention; 30 Fig. 2 is a view in side elevation; Fig. 3 is an end view of the bearing sleeve, and Fig. 4 is a plan view of the cap.

1 represents a bearing sleeve having an interior curved face 2 which serves as a 35 bearing for the rounded or spherical head 3 of a staybolt 4.

The sleeve 1 is provided at its outer end with an annular flange 5 having diametrically opposite recesses 6 and within the confines of said annular flange the bearing seat is formed with a seat 7 for a cap or closure 8. The peripheral portion of the annular flange 5 is recessed as at 9, whereby 45 segmental shoulders 10 are formed for cooperation with segmental shoulders 11 on the edge of a locking head 12.

The cap or closure 8 is made concave for the accommodation of the head of the staybolt and the dimensions and configuration of 50 the concavity are such as to provide a suitable clearance 13 for the staybolt head.

The securing head 12 incloses the cap or closure 8 and is provided interiorly with cam faces 14 for coöperation with cam 55 faces 15 on the cap or closure 8, but between

the cam faces of these respective members, a yielding disk 16 is located. This yielding disk may be made of lead and may be loosely dovetailed into recesses 17—18 in the cap and head respectively.

Slots 19 are formed in diametrically opposite portions of the securing head 12 and the cap or closure 8 is provided with fingers 20 which project through these slots. In assembling the head and cap, the fingers 20 will be passed through the slots 19 and then bent downwardly to the positions shown in Fig. 1, so that when the assembled cap and head are placed on the bearing sleeve, the fingers 20 will enter the recesses 6 in the 70 annular flange 5 of said sleeve. The width of each finger 20 is appreciably less than the length of the recess 6 in the annular flange 5 in which it enters, so that the head 12 may be turned relatively to the cap to 75 permit the operation of the cams 14—15.

When the cap 8 and head 12 are placed on the bearing sleeve and the head is given a partial turn, the segmental shoulders 11 therein, will move behind the segmental 80 shoulders 10 on the bearing sleeve. At the same time, the coöperation of the cams 14—15 will operate to press the cap firmly to its seat and cause the shoulders 11 to bind against the shoulders 10,—thus securely 85 clamping or locking the parts in place. It is apparent that by a partial turn of the locking or clamping head 12 in the reverse direction, the cap will be unlocked and both the head 12 and cap 8 can be promptly removed from the bearing sleeve to give free 90 access to the head of the bolt for testing purposes.

Having fully described our invention what we claim as new and desire to secure 95 by Letters-Patent, is:—

1. In a staybolt structure, the combination with a bearing sleeve having a notched flange, of a cap to seat on said sleeve, a head inclosing said cap and adapted to engage said notched flange, cams between said head and cap, said head having slots, and fingers on the cap projecting through said slots and engaging said notched flange.

2. In a staybolt structure, the combination with a bearing sleeve having a notched flange, of a cap to seat on said sleeve, a head inclosing said cap and adapted to engage said notched flange, cams between said cap and head, a disk of yielding material 110

- between said cams, and means for limiting the turning of the cap relatively to the head.
3. In a staybolt structure, the combination with a bearing sleeve having a notched flange, of a cap to seat on said sleeve, a head inclosing said cap and having segmental shoulders to engage said notched flange, said head having slots, fingers on the cap projecting through said slots and having limited movement in notches of said notched flange and means coöperating with the head and cap to clamp the cap on the

bearing sleeve and bind the segmental shoulders of the head against the notched flange on the bearing sleeve.

15

In testimony whereof, we have signed this specification in the presence of two subscribing witnesses.

JOHN ROGERS FLANNERY.
ETHAN I. DODDS.
